UNITED STATES PATENT OFFICE.

AXEL MAGNUSON, OF NEW YORK, N. Y., ASSIGNOR TO OTIS ELEVATOR COMPANY, OF JERSEY CITY, NEW JERSEY, A CORPORATION OF NEW JERSEY.

CONTROLLING APPARATUS FOR BRAKES.

1,069,670.

Specification of Letters Patent. Patented July 29, 1913.

Application filed September 28, 1907. Serial No. 334,691.

To all whom it may concern:

Be it known that I, AXEL MAGNUSON, a citizen of the United States, residing in New York, in the county of New York and State 5 of New York, have invented a new and useful Improvement in Controlling Apparatus for Brakes, of which the following is a specification.

My invention relates to brake mechanism 10 and means for controlling the same, and one object of the invention is to provide means for applying the brake shoes gradually and at the same time quickly and powerfully, and so that they will be held with full force 15 when the machine has come to a stop.

In practice, where a powerful brake is required, great difficulty has been experienced in adjusting the brake so that it would be applied gradually and at the same time have 20 its full braking power retained when the machine is at rest. Particularly in traction elevators it has been found that the tendency of the powerful brakes that are used is to exert their full braking power 25 suddenly, so that slipping of the ropes or cables is caused every time the brakes are applied. This results in great strain and wear of the cables, an irregular or jerky movement of the car and other undesirable 30 effects.

The present invention aims to overcome these objections by providing means for applying the brakes gradually and smoothly, with an increasing power which is retained 35 when the brake is fully applied.

Another object of the invention is to provide means in connection with an elevator system for automatically applying the brakes very quickly and with their full 40 power near the upper and lower limits of travel of the elevator car, in case the brakes have not been applied manually before the car reaches such positions.

Another object is to provide means to automatically accelerate the application of the 45 brakes when the car is approaching its limits of travel and the manual controlling lever for the brakes has been operated, but not in time to bring the car to a full stop 50 at its normal limit of travel by the more gradual application of the brakes which occurs in the ordinary operation.

A further object of the invention is to provide means, either mechanical or elec-

trical, and under the control of the operator, for applying the brakes very quickly at any intermediate point in the travel of the car. This emergency brake control is separate from and operates the brakes more quickly and powerfully than the regular 60 brake controller.

Other objects of the invention will appear more fully hereinafter, and the nature and scope of the invention will be defined in the appended claims.

Referring to the drawings, Figure 1 is an elevation partly in section and partly diagrammatic, showing one form of the invention; Fig. 2 is a fragmentary view showing certain modifications; and Fig. 3 is a 70 sectional detail view of a valve.

I have shown the invention in connection with a traction elevator system, in which the elevator car C is operated by the motor M connected thereto through the cable 1. 75 The cable 1 is connected at one end to the car C, passes over the overhead sheaves 2, 3, down and beneath the sheave 4 on the motor shaft, up and over the overhead sheaves 5 and 6, and has connected to its other end 80 the counterweight W. The above arrangement of parts is not new, but is merely illustrative of a well known form of elevator system to which the present invention may be applied.

The brake mechanism B comprises two brake levers 7, 8, pivoted at their lower ends to the brackets 9 on the motor frame. Pivoted to the brake levers are the brake shoes 10 in position to engage the brake pulley 11 90 on the motor shaft. Above the brake shoes are toggle links 12 pivoted at their outer ends to the levers 7, 8 and pivoted at their inner ends to a rod 13. The rod 13 forms an extension of the armature 14 of an 95 electromagnet, or brake magnet 15. The winding 16 of the brake magnet is in an electric circuit 17, connected to any suitable source of current supply. This circuit may be manually controlled by the hand switch 18 in 100 the car C. Between the frame of the magnet 15 and a plate 19 on the rod 13 is a coil spring 20 which is under compression and normally acts through the toggle links to pull the brake levers 7 and 8 toward each 105 other and apply the brake shoes 10 with a powerful pressure. When the switch 18 is closed to energize the magnet coil 16, the

armature 14 is drawn upwardly against the tension of the spring 20 and releases the brake.

Connected to or formed integral with the 5 electro-magnet frame is a dash-pot 21 which is formed with a horizontal cylinder and is provided with two pistons 22 and piston rods 23. The piston rods are connected by links 24 to the upper ends of the levers 7 and 8. 10 On the upper part of the dash-pot is a relief valve 25 which is preferably a plain slide valve provided with an opening or passageway 26 movable into alignment with the passageway 27 leading into the dash-pot cylinder 15 at a point midway between its ends. At the lower side of the dash-pot is a valve 28 (see Fig. 3) for controlling the air outlet 29 leading from the lower central portion of the cylinder. By adjusting this valve the 20 size of the outlet may be adjusted to regulate the escape of air from the cylinder when the brakes are being applied. To permit an unrestricted supply of air to the cylinder when the brakes are being released, an inlet 25 valve 30 is provided. This valve is seated in an enlargement of the air passage 31, leading to a point in the passageway 29 above the valve 28. This check valve 30 prevents an outward escape of air, but when the pistons 22 are moved outwardly the valve is 30 lifted off its seat by atmospheric pressure and permits a ready supply of air to the cylinder.

The relief valve 25 is operated by a lever 32, pivoted at its lower end to a lug 33 on the end of the dash-pot, and connected to the stem of the valve 25 by a pivot 34. In order to operate the valve 25 automatically as the elevator car C approaches its upper 40 and lower limits of travel, the following means is provided: A rod 35 is pivoted at 36 to the lever 32 and is movable longitudinally in stationary guides 36, 37. A coil spring 38 under compression between the fixed 45 guide 36 and a stop 39 carried by the rod 35, holds said rod normally in the position shown, with the roller 40 on the end of the rod in the path of movement of a cam 41 carried by the car C. The counterweight W 50 also carries a cam 42 which engages the roller 40 when the counterweight descends and the car approaches its upper limit of travel. Additional means is also provided for operating the valve 25 manually at any 55 intermediate point in the travel of the car. This comprises a hand rope 43 connected at its opposite ends to a slide bar 44. The rope 43 passes over the overhead direction pulleys 45, down through the car and underneath 60 the pulleys 46. The bar 44 is movable up and down in the guides 47, and is provided with a recess 48 which forms a cam surface. Pivoted to the upper end of the lever 32 is a rod 49 movable longitudinally 65 in the guide 50, and carrying a roller 51 on

its inner end which engages the cam surface 48. When the hand rope 43 is moved in either direction the slide bar 44 is moved either up or down, forcing the rod 49 outwardly, and operating through the lever 32 70 to move the valve 25 inwardly. Associated with the hand rope 43 is a switch for opening the circuit of the brake magnet whenever the hand rope is operated. This switch comprises a fixed contact 53 and a movable 75 contact 54 in the circuit 17. The contact 54 is carried by a lever 55 pivoted at 56. The end of the lever 55 has an opening through which passes the rope 43. Stop balls 57 and 58 secured to the rope 43 above and below 80 the lever 55 respectively engage the lever and swing it about its pivot to open the switch whenever the rope is operated in either direction.

The operation of the brake mechanism 85 thus far described is as follows: With the switch 18 open, the brakes are applied and the motor is at rest. When the switch 18 is closed the magnet coil 16 is energized and pulls the armature 14 upwardly, which operating through the toggle links 12 moves the levers 7 and 8 outwardly to release the brakes. This outward movement of the levers 7, 8, moves the pistons 22 apart, the valve 30 permitting a free supply of air between 90 the pistons so that their outward movement is unrestricted. The relief valve 25 at this time and during the ordinary operation of the brake mechanism, remains closed as shown in the drawing. The motor circuit 100 may also be controlled in a well known manner by the switch lever 18, so that when said lever is operated to release the brake, current is supplied to the motor and the car C is set in motion. When it is desired to stop 105 the car the switch lever 18 is moved to open the motor circuit and also open the circuit of the brake magnet. When the brake magnet is thus deenergized, the coil spring 20 operates through the toggle links 12 to pull 110 the levers 7 and 8 inwardly with a strong pull and powerfully apply the brakes. The pressure exerted by the spring 20 is multiplied in a well known way by the toggle connections. The pressure on the brake shoes 115 is further multiplied by arranging the brake shoes between the toggle links and the pivots of the levers 7 and 8. The pressure thus put on the brakes is not applied suddenly, but is cushioned by the action of the dash-pot. 120 As the levers 7, 8, move inwardly to apply the brakes, the pistons 22 are moved inwardly compressing the air between them. The compressed air re-acts against the levers, retarding their inward movement, the 125 speed of which is controlled by adjusting the valve 28 to regulate the escape of air from the cylinder. The pressure of the air will be proportional to the area of the pistons, and I prefer to use a rather large dash- 130

pot in order to get sufficient back pressure to fully control the speed with which the brakes are applied. By using a rather large volume of air a practically perfect cushioning effect is obtained, effectively preventing any unevenness or jerkiness in applying the brakes. Another advantage of having a large volume of air is that the effects of any irregularity due to leakage of air is practically overcome.

The pistons 22 are preferably fitted to work freely in the cylinder without any packing, and the piston rods 23 should also work freely in the cylinder heads without any stuffing boxes or other packing. The openings in the cylinder heads for the piston rods should be large enough to permit a free ingress and egress of the air as the pistons operate. The cylinder heads may be omitted entirely if desired.

The relief valve 25 is preferably a plain plug valve, freely fitted in its bearings, so that there will be no danger of it ever sticking.

The pistons being connected at the ends of rather long levers 7, 8, considerable leverage is gained and the power of the dash-pot multiplied. With this leverage and the use of a rather large dash-pot, very powerful brakes may be used and yet be under the complete control of the cushioning device, so that they are gradually and smoothly applied.

An important feature of this construction is that, although the brakes are applied gradually and smoothly, they hold with their full power, which is not relaxed except at the will of the operator.

The above described operations take place in the ordinary stopping and starting of the elevator. When, however, it is desired to apply the brakes very quickly, as in case of an emergency, the operator simply grasps the rope 43, which will give the rope a downward pull if the car is descending or an upward pull if the car is ascending. This movement of the rope will move the bar 14 either up or down, depending on the direction of pull of the rope, and in either case the rod 49 will be forced outwardly, carrying with it the lever 32, and moving the relief valve 25 into alignment with the air duct 27. Simultaneously with this movement, or immediately following it, one of the stops 57, 58, will engage the switch lever 55, moving it about its pivot and opening the circuit 17 of the brake magnet. The magnet being thus deenergized, the spring 20 immediately acts to quickly and powerfully apply the brakes. The air duct 27 being open, the air between the pistons 22 can readily escape as the pistons are moved inwardly in applying the brake, so that no cushioning or retarding occurs, and the brake is applied much quicker than in the

ordinary operation where the dash-pot is operative as a retarding device.

In case the operator fails to operate the brake switch in time to bring the car to rest at its normal limit of travel in either direction, by the ordinary operation of the brakes, the cam 41 or the cam 42, as the case may be, will engage the roller 40 and move the rod 35, operating the valve 25, and allowing a quick application of the brakes.

In Fig. 2 is shown a modified construction. The relief valve 25 is here carried by a rod 60 which is connected to the core 61 of an electro-magnet 62. The core 61 is normally held against a stop 63 by a spring 64 bearing against an extension 65 of the valve 25. The other end of the spring 61 bears against a stop 66, adjustable by means of the set screw 67 to vary the tension of the spring. When the electro-magnet 62 is energized the core 61 is pulled away from the stop 63 into the position shown in Fig. 2, in which the port 27 is closed. When the magnet is deenergized, the spring 64 moves the core 61 against the stop 63 and the opening in the valve 25 is brought into alignment with the port 27, admitting air into the dash-pot.

There are two switches in the circuit of the electro-magnet 62, namely, the hand switch 68 and the automatic switch 69. The switch 69 has two fixed contacts 70 and 71 spaced apart, and a contact 72 movable into position to bridge the contacts 70 and 71. The contact 72 is carried by, but insulated from, a lever 73 pivoted at 74 to the switch base. The lever 73 carries a roller 75 in position to be engaged by the cams 41 and 42 on the car and counterweight, respectively. The switch 69 is normally held in a closed position by a spring 76. The hand switch 68 is connected to the positive main by the wire 77. A wire 78 connects the contact 79 of the hand switch with the contact 71 of the switch 69. The contact 70 is connected by the wire 80 to one terminal of the magnet coil 62, while the other terminal of said coil is connected to the negative main by the wire 81. A switch lever 82, pivoted at 83 to a fixed support, is connected at its lower end to the rod 60, while its upper end carries a contact 84. The contact 84 is in engagement with a fixed contact 85 when the electro-magnet 62 is energized and the valve 25 closed, but when the magnet is deenergized and the valve moved to open position the contact 84 is moved out of engagement with the contact 85. One terminal of the brake magnet coil 16 is connected by a wire 86 to the movable contact 84, while the other end of said coil is connected by a wire 87 to the negative main. The contact 85 is connected by a wire 88 to a fixed contact 89 of the hand switch 90. The two hand switches 90 and 68 are electrically connected by a

wire 91. The switch 69 is connected to the positive main by the wire 92. A wire 93 connects the contact 79 of the hand switch with the contact 71 of the switch 69. The contact 70 is connected by the wire 94 to one terminal of the magnet coil 62, while the other terminal of said coil is connected to the negative main by the wire 95. A switch lever 96, pivoted at 97 to a fixed support, is connected at its lower end to the rod 60, while its upper end carries a contact 98. The contact 98 is in engagement with a fixed contact 99 when the electro-magnet 62 is energized and the valve 25 closed, but when the magnet is deenergized and the valve moved to open position the contact 98 is moved out of engagement with the contact 99. One terminal of the brake magnet coil 16 is connected by a wire 100 to the movable contact 98, while the other end of said coil is connected by a wire 101 to the negative main. The contact 99 is connected by a wire 102 to a fixed contact 103 of the hand switch 90. The two hand switches 90 and 68 are electrically connected by a

wire 91. A push button switch 92 has its movable contact connected by a wire 93 to the fixed contact 85. The fixed contact 94 of the push button switch is connected to the wire 88. It is to be understood that the illustration of the switches and circuits is largely diagrammatic, and that the switches 68, 90 and 92 are in practice usually located in the elevator car. The invention, however, is adapted for use also with elevators controlled from a switchboard outside the car.

The operation of the devices shown in Fig. 2 will now be described.

15 The switch 68 is normally retained in its closed position. This maintains a closed circuit through the magnet 62 as follows: from the positive main through wire 77, switch 68, contact 79, wire 78, contacts 71, 72, 70, wire 80, magnet coil 62, wire 81 to the negative main. The magnet 62 is thus normally energized, maintaining the valve 25 in its closed position. The brake magnet is controlled in the ordinary operation of the elevator by the switch 90 corresponding to the switch 18 of Fig. 1. When this switch is closed, the following circuit through the brake magnet coil 16 is closed: from the positive main through wires 77, 91, switch 90, contact 89, wire 88, contacts 85, 84, wire 86, magnet coil 16 and wire 87 to the negative terminal. The brakes are then released. When the switch 90 is opened the circuit through the brake magnet is broken and the brakes are applied, the dash-pot operating as before explained to permit the brakes to be applied gradually and smoothly. If, when the car is ascending or descending, the operator fails to open the brake switch in time to bring the car to a full stop by the ordinary operation of the brake before the car reaches its normal limit of travel, one of the cams 41, 42, will engage the roller 75 and open the switch 69. This opens the circuit through the coil 62 which is thus de-energized and the valve 25 moved to the right, opening the port 27 and allowing a quick operation of the brakes, the same as in Fig. 1. But in addition to opening the 50 valve 25, the rod 60 in its movement to the right moves the switch lever 82, separating the contacts 84, 85. This will not affect the operation in any way if the switch 90 has been opened before the automatic switch 69 has been opened, the circuit of the brake magnet simply being opened at two places. But if the operator fails to open the switch 90 before the automatic switch 69 has operated, the brakes will be applied entirely 55 automatically. That is, the opening of the switch 69 will operate to open the valve 25, and at the same time open the switch 84, 85 in the brake magnet circuit, so that the brakes will be quickly applied. If at any 60 time when the switch 90 is closed and the 65

elevator running, the operator desires to apply the brakes quickly, he can open the switch 68 which opens the circuit of the magnet coil 62 and is equivalent to opening the switch 69, and operates the brakes in 70 the same way.

The purpose and operation of the push button switch 92 which controls a shunt circuit around the switch 82 is as follows: If the car or counterweight has moved into position to hold the switch 69 open, the switch 82 which is in the brake magnet circuit will remain open, so that the operator cannot release the brakes by closing the switch 90. But while the switch 90 is closed he can 80 close the push button switch, which will close the shunt circuit around the switch 84, 85, closing the brake magnet circuit and releasing the brakes.

I have shown my invention as applied to 85 a traction elevator system, but it is applicable to other elevator systems, and also to brakes used for various other purposes. I have shown various operating and controlling devices, both electrical and mechanical, 90 manually operable and automatic, and various other devices might be used within the spirit and scope of my invention. I do not, therefore, wish to be limited to the exact constructions and arrangements of parts 95 shown and described.

What I claim as new and desire to secure by Letters Patent of the United States is:—

1. The combination with a plurality of 100 brake levers, a plurality of brake shoes, and means to operate the said levers, of an air cylinder, a plurality of pistons movable in the cylinder to compress the air, corresponding piston rods, and connections between the piston rods and the brake levers.

2. The combination with a plurality of 110 brake levers, of a plurality of brake shoes, means for operating the levers, an air cylinder, pistons movable in the cylinder to compress the air, piston rods, connections between the piston rods and the brake levers, and means to permit a gradual escape of the air from the cylinder.

3. In a brake mechanism, the combination with a pair of brake levers, brake shoes connected to the levers, and means for moving the brake levers toward each other and thereby applying the brakes, of an air cylinder located between the brake levers, pistons in the cylinder confining and compressing the air in the cylinder while the brakes are being applied, and connections between the pistons and the brake levers.

4. The combination with a brake and means for operating the brake, of means 125 for retarding the operation of the brake, and automatically operated means for rendering the retarding means inoperative.

5. The combination with a brake and means for operating the brake, of mecha- 130

- nism opposing the quick application of the
5 brake, means separate from the opposing
mechanism for rendering the opposing mech-
anism inoperative, and a single device for
controlling the operation of both of said
means.
6. The combination with a brake and
operating means therefor, of a dash-pot con-
10 nected to and retarding the operation of
the brake, an air duct leading from the
dash-pot, and a valve normally closing said
duct, but movable into position to open said
duct and permit a free escape of air from
the dash-pot.
- 15 7. The combination with a brake and op-
erating means therefor, of a dash-pot con-
nected to and retarding the operation of the
brake, a restricted passageway communicat-
20 ing with the dash-pot to permit a gradual
escape of the air, and a relief valve connect-
ed to the dash-pot and movable into position
to permit a free escape of air from the
dash-pot.
- 25 8. In a brake mechanism, the combination
with brake levers, of brake shoes connected
to the levers, means for moving the brake
levers toward each other to apply the brakes,
an air cylinder, pistons movable toward and
30 from each other in the cylinder, connections
between the pistons and brake levers, an air
duct leading into the cylinder between the
pistons, a valve in said duct restricting the
escape of air from the cylinder, a second air
35 duct leading into the cylinder, and a valve
normally closing said duct, but movable into
position to permit a free escape of air from
the cylinder.
- 40 9. The combination with a brake and
means for applying the brake, of means for
retarding the application of the brake, and
a device for controlling the operation of
both of said means.
- 45 10. The combination with a brake and
means for applying the brake, of a device
45 for retarding the application of the brake,
and a manually operable device for render-
ing the retarding device inoperative and con-
trolling said brake-applying means.
- 50 11. The combination with a brake and
means for applying the brake, of a dash-pot
device for retarding the application of the
brake, and a device for rendering the re-
tarding device inoperative and controlling
55 the brake-applying means at a single oper-
ation.
- 60 12. The combination with a brake and an
electro-magnet for operating the brake, of a
dash-pot normally retarding the applica-
tion of the brake, a relief valve for the dash-
pot, a manual switch in the electro-magnet
65 circuit, a second switch in the circuit, and a
single means for operating the relief valve
and said second switch.
- 65 13. The combination with a motor, of a
brake, a retarding device for the brake, and
automatic means for controlling the retard-
ing effect of said device.
14. The combination with a motor, of a
brake, a retarding device for the brake, and
70 automatic means for rendering the retard-
ing device ineffective under predetermined
conditions.
15. The combination with a motor, of a
brake, a dash-pot connected to and nor-
75 mally retarding the application of the
brake, a relief valve on the dash-pot, and
means for automatically opening the relief
valve.
16. The combination with a motor, an
electro-magnetic brake, and a manual switch
80 for controlling the brake magnet circuit, of
a dash-pot connected to and normally re-
tarding the application of the brake, a relief
valve for the dash-pot, and means for auto-
matically opening the relief valve.
17. The combination with a motor, and a
brake, of a dash-pot connected to the brake
and normally retarding its application, a
normally closed relief valve for the dash-pot,
85 a movable cam, a device extending into the
path of the cam, and operative connections
between said device and the relief valve.
18. The combination with a motor, of a
brake, a retarding device for the brake, and
90 automatic means for controlling the retard-
ing device.
19. The combination with a motor, of a
brake, a retarding device for the brake, and
95 automatic means for controlling the retard-
ing effect of said device.
20. The combination with a motor, an
electro-magnetic brake, and a controlling
100 switch for the brake magnet circuit, of a re-
tarding device for the brake, and means for
rendering said device ineffective and control-
ling the brake magnet circuit at a single
operation.
21. The combination with a motor, an
electro-magnetic brake, and a switch con-
110 trolling the brake magnet circuit, of a dash-
pot connected to the brake and normally
retarding its application, a relief valve for
the dash-pot, and means operating said re-
lief valve.
22. The combination with a motor, and a
brake, of a retarding device for the brake,
115 means for automatically rendering said de-
vice ineffective at predetermined periods,
and a manual device for rendering the re-
tarding device ineffective and applying the
120 brake.
23. The combination with a motor, and a
brake, of means for retarding the applica-
125 tion of the brake, and automatic means for
rendering the retarding device ineffective
and applying the brake.
24. The combination with a motor, of a
brake, a dash-pot connected to the brake
and normally retarding its application, a
130 relief valve for the dash-pot, and means for

automatically opening the relief valve and applying the brake.

25. The combination with a motor, and an electro-magnetic brake, of a dash-pot connected to the brake and normally retarding its application, a relief valve for the dash-pot, an electro-magnet controlling said valve, and a switch controlling the circuits of said electro-magnet and the brake magnet.

26. The combination with a motor, and an electro-magnetic brake, of a dash-pot connected to the brake and normally retarding its application, a relief valve for the dash-pot, an electro-magnet controlling said valve, a switch controlling the circuit of said electro-magnet and the brake magnet, and means for automatically operating the switch.

20 27. The combination with a motor, and an electro-magnetic brake, of a dash-pot connected to the brake and normally retarding its application, a relief valve for the dash-pot, a switch in the brake magnet circuit, an electro-magnet controlling the relief valve, and a switch controlling the circuits of the brake magnet and said controlling electro-magnet.

28. The combination with a motor, and an electro-magnetic brake, of a dash-pot, a relief valve for the dash-pot, an electro-magnet controlling said valve, and a switch in the brake magnet circuit also controlled by said electro-magnet.

30 29. The combination with a motor, and an electro-magnetic brake, of a dash-pot connected to the brake, a relief valve for the

dash-pot, a device for opening the relief valve, and a switch in the brake magnet circuit connected to said device and opened 40 when the valve is opened.

30. The combination with a motor, and an electro-magnetic brake, of a dash-pot connected to the brake, a relief valve for the dash-pot, a device for opening the relief 45 valve, a switch in the brake magnet circuit connected to said device and opened with the valve, a shunt circuit around said switch, and a switch in the shunt circuit.

31. The combination with a motor, and an 50 electro-magnetic brake, of a dash-pot connected to the brake and normally retarding its operation, a relief valve for the dash-pot, an electro-magnet connected to the relief valve and holding it closed when the magnet 55 is energized, means for opening the valve when the magnet is deenergized, an automatic switch in the circuit of said electro-magnet, means for holding said switch normally closed, a manually operable switch in 60 said circuit, a switch in the brake magnet circuit operatively connected with the relief valve, a shunt circuit around said last-named switch, a manual switch in the shunt circuit, and a manual switch in the brake 65 magnet circuit.

In testimony whereof, I have signed my name to this specification in the presence of two subscribing witnesses.

AXEL MAGNUSON.
